Primary Examiner — Keli L Hill(74) *Attorney, Agent, or Firm* — Eugenio J. Torres-Oyola; Victor M. Rodriguez-Reyes; Rafael Rodriguez-Muriel(57) **CLAIM**

We claim the ornamental design for a wireless speaker, as shown and described.

DESCRIPTION

FIG. 1 is a front view of a wireless speaker showing my new design;

FIG. 2 is a rear view thereof;

FIG. 3 is a left-side view thereof;

FIG. 4 is a right-side view thereof;

FIG. 5 is a top view thereof;

FIG. 6 is a bottom view thereof;

FIG. 7 is a front perspective view thereof; and

FIG. 8 is a rear perspective view thereof;

FIG. 9 is a front view of another wireless speaker showing my new design;

FIG. 10 is a rear view thereof;

FIG. 11 is a left-side view thereof;

FIG. 12 is a right-side view thereof;

FIG. 13 is a top view thereof;

FIG. 14 is a bottom view thereof;

FIG. 15 is a front perspective view thereof;

FIG. 16 is a rear perspective view thereof; and,

FIG. 17 is an exploded view thereof.

The shade lines shown in the drawings indicate the character and contour of surfaces represented and should not be confused with surface ornamentation.
